[57] ABSTRACT

In an indexing control device for a tool storage magazine having a plurality of index positions, each of which has a specific decimal number coded by binary coded decimal elements, the tool storage magazine is divided into a plurality of regions by means of the upper figures of the decimal numbers. The index control device comprises first and second discriminating circuit means, one of which selects the rotating direction of the magazine in to index the region including the desired index position to a predetermined position in a shorter route by means of the upper figure, and the other of which selects the rotating direction to index the desired index position to the predetermined position in a shorter route by means of the subordinate figure of the decimal number after indexing of the region.

**DIGITAL FINE-COARSE RAPID INDEXING
MOTOR CONTROL INCLUDING MEANS TO
SENSE SHORTEST DISTANCE**

SUMMARY OF THE INVENTION

This invention relates to an indexing control device for a rotating body having a plurality of index positions, and more particularly relates to a rapid indexing control device which indexes a desired index position of the rotating body, such as a tool storage magazine of a machine tool provided with an automatic tool changer, to a predetermined station in a shorter route.

Outlining the method as performed by the device of the present invention, a tool-identifying means identifying the tool-receiving portions of a rotating body is provided in the automatic tool-changer in order that the rotating motion of the rotating body in a forward or reverse rotating direction is controlled by means of the tool-identifying means to index a desired and commanded tool, or a commanded tool-receiving portion of the rotating body, rapidly to a predetermined tool-change position or a predetermined machining position of machine tools.

On the other hand, it is generally known that a tool-storage magazine of a machine tool is rotated after being discriminated as to which of the two routes in the forward or reverse rotating direction thereof is shorter. However, it has not been known heretofore for each tool receiving portion of the magazine to be given a code relating to each kind of work tool and the selection of a desired tool out of the work tools as well as the discrimination of the shorter route for the rotating body in a forward or reverse rotating direction in order for the selected tool receiving portion to arrive at the predetermined tool change position, to be performed on the basis of the codes of the coded tool-receiving portions.

Recently, according to machine tools provided with an automatic tool changer which are widely used, it is necessary that the machine tool is capable of performing many kinds of complicated machining processes. As a result of this, the number of stored tools in the magazine is inevitably increased and accordingly, the size of the magazine increases.

Therefore, it became clear that coding the identifying symbols of the tools is more effective and economical for identification of a large number of work tools than to simplify a large number of identifying elements of the work tools. Accordingly, the tool-storage magazine, provided with a code device relating to the tool receiving-portions of a so-called address-type tool magazine, each of which corresponds to each work tool, is widely adopted. Thus, it has been widely applied to code the tool-receiving portions of the tool-storage magazine, but the tool magazine could not be rotated in more than one direction to detect the commanded tool and consequently, it often occurred that the tool magazine had to be rotated by almost one complete rotation to obtain a desired tool, even if the desired tool had been positioned adjacent to the tool in the actual index position. Thereupon, if the magazine is discriminated as to which of the two routes is shorter in a forward or reverse rotating direction of the magazine to index the stored position of the commanded tool, to the tool change position, it is possible to take the desired and commanded tool out of the tool magazine

with the rotating motion of the magazine by less than 180 degrees and it is also possible to shorten the tool-section time.

Taking this into consideration, the present invention provides the following features and advantages.

In accordance with one of the features of the present invention, each of the index positions of the rotating body, such as a tool-storage magazine, is given a code and by applying each code, the shorter rotating direction of a desired index position to a predetermined tool-change position is discriminated to control the rotating direction of the above-mentioned rotating body. Also, in the case when there is a large number of index positions, the entire index positions are divided into a plurality of groups. There is provided a rotating direction-discriminating means to the automatic tool changer, responding to the above-mentioned code, which controls the rotating direction of the rotating body so as to be rotated in the shorter route by discriminating the difference between the groups of the actual index position and the subsequent desired index position by applying the above-mentioned code. (The actual position is defined hereinafter as the index position which has been indexed to the position read by the reading device.)

The rotating direction-discriminating means also controls the direction of the body so as to be rotated in the shorter route in case the actual and subsequent desired index positions belong to an identical group.

Therefore, as the rotating direction-discriminating means is operated first in response to only the code which commands the group, the device can consist of simple logical circuits even if a large number of work tools is used. Also, in the case when the actual and subsequent desired tools belong to an identical group, the logical circuits for discriminating the rotating direction also consist of the comparatively simple arrangement of circuits, since the number of index positions belonging to each group can be reduced and the same logical circuits can be applied commonly to each group.

Consequently, the binary-coded decimal code can be used as a preferred example of the above-mentioned code.

When the binary-coded decimal code is applied, it is possible to apply the upper figures of the decimal code to the discrimination of the difference between the groups, and the subordinated figure of the decimal code to the discrimination of the rotating direction in case the actual and subsequent commanded index positions belong to an identical group.

Besides, since each group has the same unit figure-code arrangement, the same rotating direction-discriminating means by applying the unit figure-code can be used in common in every group.

Therefore, it is an object of the present invention to provide a quick index-control device for a rotating body which can discriminate the shorter rotating route in a forward or reverse rotating direction of a so-called address type tool magazine, wherein various kinds of tools related to a plurality of tool-receiving portions are discriminated by the tool identifying code corresponding to the tool-receiving portions.

Another object of the present invention is to provide a quick index-control device for a rotating body which can discriminate the shorter rotating route in a forward

or reverse direction of the tool-storage magazine, of which, the work tool-storage region is divided into a plurality of regions by applying the tool-identifying code, while being discriminated as to whether both tool storage regions of the actual and subsequent command tools are identical or different.

A further object of the present invention is to provide a quick index-control device for the rotating body which can control the tool-storage magazine so as to rotate along the shorter rotating route in a forward or reverse direction while discriminating whether both storage regions of the actual and subsequent commanded tools are identical or different by applying the binary code corresponding to the upper figure of the decimal code used as the above-mentioned tool identifying code, as well as by applying the binary code corresponding to the subordinate figure of the decimal code in case both the above-mentioned storage regions are discriminated to be identical.

The foregoing and other objects of the present invention will become fully apparent from the following descriptions of preferred embodiments of the present invention with reference to the accompanying drawings, in which:

FIG. 1 is a front elevation view of a machine tool having an automatic tool-changer,

FIG. 2 is a perspective view of a model of the tool-storage magazine forming a part of the automatic tool changer,

FIG. 3 is a partially cut out developed view of an embodiment of the coding drum forming identifying codes by a dog arrangement,

FIG. 4 is a schematic plan view of the magazine for illustrating the operation theory of the present invention,

FIG. 5 is a diagram of the control circuit for the electric power circuit of a drive motor for the tool-storage magazine,

FIG. 6 is a diagram of the relay circuit responding to the tape command and the code of the dog arrangement according to an embodiment of the present invention,

FIG. 7 is a diagram of the relay circuit for converting a binary number to a decimal number according to an embodiment of the present invention,

FIG. 8 is a diagram of the detecting circuit for the coincidence of the commanded storing region with an indexed storing region according to an embodiment of the present invention,

FIG. 9 and FIG. 10 are diagrams of the direction-discriminating circuits according to an embodiment of the present invention, in which the rotating direction of the magazine is controlled by discriminating the difference between the storing regions of the actual and subsequent commanded tool,

FIG. 11 and FIG. 12 are diagrams of the direction-discriminating circuits to control the rotating direction of the magazine within an identical storing region according to an embodiment of the present invention,

FIG. 13 is a diagram of the detecting circuit for the coincidence of the commanded tool and indexed tool according to an embodiment of the present invention,

FIG. 14 through FIG. 17 are schematic plan views of the magazine and diagrams of the electric control circuits for illustrating another modified embodiment according to the present invention in which FIG. 14 is a schematic plan view of the magazine,

FIG. 15 is a diagram of the modified detecting circuit of FIG. 8,

FIG. 16 is another modified direction-discriminating circuit of FIG. 9 and FIG. 10,

FIG. 17 is a diagram showing a part of another modified coincidental circuit of FIG. 13.

FIG. 1 shows a whole arrangement of a machine tool having an automatic tool changer, wherein reference numeral 1 is a bed on which is arranged a column 2 having a vertical sliding surface 3 formed thereon for slidably guiding a spindle head 4.

This spindle head 4 is threadedly engaged with feed screws, (not shown), which are operated by a motor 6 through a reduction mechanism 5 so that the head 4 is given a vertical feed motion.

The spindle head 4 is provided with a power-driven main spindle 7 rotatably mounted thereon and formed in a socket at the end thereof which receives various kinds of removal tools T, and contains a tool clamping mechanism. Reference numeral 8 is a cylinder for counter-balance against the weight of the head 4. A chain 9 is connected at its end to the end of the piston rod of the cylinder 8 and connected to the spindle head 4 at the other end thereof, so that the weight of the spindle head 4 is balanced by means of hydraulic power.

On the bed 1, a guide way 10 is formed along the axis of the spindle 7 to slidably guide a saddle 11 on top of which a guide way 12 is formed along an axis perpendicular to the axis of the spindle and guides a work table 13.

A workpiece W is mounted on a power driven index table 14 rotatably arranged on the top of the work table 13, so that each different surface of the workpiece faces the spindle 7 by the necessary dividing operation of the index table 14. The above-mentioned saddle 11 and work table 13 are engaged with each other by respective feed screws (not shown), which are operated by motors 17 and 18 through the reduction mechanisms 15 and 16. The above-mentioned motors 6, 17 and 18 are operated in response to the command transmitted from a numerical control apparatus (not shown), to give a feed motion in three-dimensional directions. A drive motor of the index table 14 is similarly controlled by the command from the numerical control apparatus.

Many kinds of systems may be applied to the automatic tool changer to change the tools of the spindle provided for the above-mentioned spindle head 4. In the embodiment shown in FIG. 1, the automatic tool changer comprises a plurality of supporting pillars 20, a chain-type tool-storage magazine 22 disposed on a base plate 21 supported on the top of the pillars 20 over the column 2, a tool-indexing apparatus 23 which indexes each socket 22a of the magazine 22 to a predetermined tool change position TCP, a sub arm 24 removing or returning a tool T at this tool-change position, a tool-holding socket 27 rotatably supported on a bracket 26 secured to a carriage 25 following the displacement of the spindle head 4, and a main change arm 28 which is rotatably mounted on the top portion of the spindle head 4 and changes tools in the tool-holding socket 27 and the spindle 7 simultaneously. The above-mentioned carriage 25 is slidably supported by the guide bars 30 arranged on the column 2, and has an arrangement in which the carriage 25 travels along the center

of the spindle 7 while maintaining a predetermined relative position as shown in FIG. 1, by feed screws 32 which are operated by a motor 31 actuated by a follow-up type servovalve (not shown). The carriage 25 can also be moved to the position where the tools are delivered by the above-mentioned sub arm 24, when the carriage 25 is released to travel along the center of the spindle 7. The tool-holding socket 27, which moves together with the carriage 25, is adapted to be pivoted by 90° to a ready position from the shown waiting position where the socket 27 is free from interference with the workpiece W. The tool is removed by the axial movement of the sub arm 24 from the magazine 22 to the socket 27, being transferred by the main arm 28 from the socket 27 to the main spindle 7 when the tool socket 27 is in the axially horizontal situation after it has been pivoted by 90° from the waiting position. The detailed arrangement of the index apparatus 23 for the magazine 22 is shown in FIG. 2 as an example according to the present invention.

The roller chains 56 connecting a plurality of sockets 22a with each other, are provided with chain rollers 57 engaged with a plurality of sprockets 23, one of which is shown in FIG. 2, which are rotatably mounted on the above-mentioned base plate 21 by means of a supporting shaft 33.

One of the sprockets 32s which is shown in FIG. 2, cooperates with the output shaft 40 of a motor M1 having a brake, through a worm wheel 34 mounted on the supporting shaft 33, a worm 35, a worm-shaft 36, a spline-coupling 37, and gears 38 and 39. An index plate 41 fixed coaxially on the supporting shaft 33 is provided with notches 41a formed therein, of which, a pitch corresponds to the pitch between each socket 22a. Adjacent the notches 41a, there is provided a plunger 43 reciprocally moved into and away from the notches 41a by a hydraulic actuator 42.

At the rear of this actuator 42, there protrudes a rod 42a having a dog 44 at the end thereof and a limit switch LSQ adjacent the dog 44.

The dog 44 operates the limit switch LSQ to ascertain the engagement of the plunger 43 with one of the notches 41a.

A gear 45, arranged coaxially with the above-mentioned gear 38, is engaged with a gear 46. The gear 46 is connected to a dog-holding plate 47 which rotates a full turn depending on the rotation of the socket 22a by one pitch. A dog 48 secured to this holding plate 47, operates a limit switch LSD to make an "And" condition when the discriminating code on the later-explained coding drum is read.

At the front end of the above-mentioned worm shaft 36, there is provided an absorbing cylinder 49 which absorbs the inertia and the over-running of the worm shaft 36 when the plunger 43 is engaged with one of the notches 41a.

The absorbing cylinder 49 cooperates with the above-mentioned spline-coupling 37 to permit a limited amount of axial displacement of the worm 35.

A coding drum 50 rotates in response to the rotating motion of the sprocket 32s. On the drum shaft 53, there is provided a gear wheel 52 engaged with a pinion 51 fixedly mounted on the supporting shaft 33 in order that the coding drum 50 can rotate by one complete rotation upon one complete rotation of the magazine 22.

On the outer peripheral surface of this coding drum 50, there are arranged dogs forming binary-coded decimal codes, as shown in FIG. 3. For example, the tool number 13 is formed by dogs arranged in the rows represented by LS1, LS2 and LS10.

Adjacent the coding drum 50, there is provided a reading device 55 having limit switches LS1, LS2, . . . and LSP thereon, corresponding to respective dog rows and operated by dogs 54 (FIG. 3).

Decimal tool numbers are code by the dog arrangement on the coding drum 50, so that it is possible to discriminate the rotating direction and the desired index position of the magazine 22 by applying these decimal codes, as described hereinafter.

As mentioned above, in case the binary-coded decimal code is applied, it is possible to divide the entire sockets 22a of the magazine 22 into several groups of ten sockets 22a so as to discriminate the groups by applying the tenth figure-code of the decimal number. Therefore, if the magazine 22 is capable of storing 60 tools, six groups of the tool-storing regions can be discriminated from each other as different codes.

It is a feature of the present invention to control the 25 rotating body, such as a tool-storage magazine, so as to be discriminated in the rotating direction thereof by applying the tool-identifying code. According to the above feature, it is possible to perform positioning of the rotating body to the commanded index position and

30 select the commanded tool in the shorter rotating route of the rotating body by discriminating the difference between the groups including the actual and subsequent command index positions and by discriminating the rotating direction of the rotating body when both index positions belong to an identical group.

The theory of operation of the device according to the present invention, will be described hereinafter as to the case in which the tool-storage magazine has 60 pieces of work tools as shown in FIG. 4.

First, if it is assumed that all the tools in the magazine 22 are arranged as shown in FIG. 4, the rotating directions of the magazine are defined as CW (clockwise) and CCW (counterclockwise) for each 45 shown arrow and all the positions are divided into six regions of 00, 10, . . . and 50 by applying the tenth figure-digits.

In the explanations hereinafter, the actual position and the subsequent commanded position of the 50 magazine are distinguished for designation purpose by attaching the symbols L and T to the respective code.

Here, the condition and the logical condition for rotating the magazine 22 in the clockwise direction are shown in Table 1, and in the counterclockwise 55 direction in Table 2.

TABLE 1

L9	T9	CCW	T8
L9	T0 - T8	CW	

For example, if the actual position in No. 31 and the subsequent commanded tool is No. 27, the condition "T20" in the row "L30" of Table 1 is satisfied, so that the rotating direction of the magazine is determined to be a clockwise direction and the tool of No. 27 can be indexed to the tool-change position with a slight amount of magazine rotation.

Further, if the tool of No. 43 is commanded subsequently, the condition "T40" in the row "L20" of Table 2 is satisfied. Consequently, the rotating direction of the magazine 22 is determined to be a counterclockwise direction. However, the condition to select a desired tool is not limited merely to the condition wherein the actual index position and the subsequent commanded tool position belong to the different groups, respectively.

When both positions belong to an identical group, the rotating direction of the magazine is determined according to the condition shown in Table 3.

For example, if the tool of No. 48 is commanded subsequent to the tool of No. 43, the rotating direction of the magazine is discriminated by discriminating the positions of each unit digit 3 and 8 of both tool numbers. That is, the rotating direction of the magazine is determined to be a counterclockwise direction according to the condition of "T4 through T9" in the row "L3" of Table 3. Thus, the necessary tool selection time can be reduced according to the discrimination of the shorter rotating route of the magazine.

The logical circuits of FIG. 9 and FIG. 10, which are described in detail hereinafter, are formed in accordance with the logical condition to Table 1 and 2, while the logical circuits of FIGS. 11 and 12, which are described in detail hereunder, are formed in accordance with the logical condition of Table 3, whereby it is possible to attain the automatic control of the rotating direction of the magazine and the selection of the tool in the shorter rotating route.

Hereinafter, the above-mentioned logical circuits will be explained with examples of the relay circuits. Referring to FIG. 5, there is shown an electric power source circuit for the motor of the magazine-index apparatus 23.

A distributing breaker CB1 is connected to electric power supply lines R, S and T.

The relay-contacts of a motor CMCW-1 for enabling the change of the rotating direction of the motor M1 are inserted and connected between the breaker CB1 and the input terminals of the motor M1 provided with a brake.

A thermal relay TY1 operates when the motor M1 is overloaded, and the normally closed contacts of the relay TY1 are connected in a series to the motor-relays CMCW and CMCCW.

Brake-contacts CRB-1 are inserted between the breaker CB1 and a brake-coil B.

The electric power supply lines R and T are connected to the primary winding of a transformer Tr1, and the secondary winding of the transformer Tr1 are connected to the electric power supply lines of the relays circuit 100 and 200 through fuses F₁ and F₂.

The relays CMCW and CMCCW, connected between the electric power supply lines 100 and 200, are energized by closing the contacts CRCW-1 and CRCCW-1 to close the above-mentioned contacts CMCW-1 or CMCCW-1 to rotate the motor M1 in a forward or reverse direction and as a result of this, the magazine 22, (FIG. 1) is rotated in a clockwise direction or a counterclockwise direction.

The stoppage of the magazine is performed by stopping the motor M1 due to the opening of the electric power source circuit depending upon the de-energizing of the motor relays CMCW and CMCCW. These motor relays CMCW and CMCCW are deenergized by opening the contacts CRCW-1 and CRCCW-1 in such a manner that when the relay CR100 of the later-described coincidental circuit of FIG. 13 is energized by a coincidental signal, which is generated by the magazine reaching the position in advance of the exact index position, the normal closed contact CR100-1 of FIG. 9 is opened to de-energize the relays CRCW and CRCCW to open the above-mentioned contacts CRCW-1 and CRCCW-1. When the magazine is stopped, the plunger 43, (FIG. 2) is moved to the forward position under the deenergization of a solenoid SOL1 and as the plunger 43 is engaged with an indexed notch 41a of the index plate 41 with the inertial rotating motion of the magazine, the limit switch LSQ is operated to energize the relay CRQ1 with closing of the contact CRQ1-2. As a result of this, a relay CRB is energized so that the braking power is applied to rapidly stop the motor M1 and its related mechanism.

The over-running of the magazine after the engagement of the plunger 43 is absorbed by the absorbing

cylinder 49, so that the commanded index position of the magazine is accurately indexed. Also, when the motor is commanded to rotate in a forward or reverse direction, the relay CRQ2 is energized to close the contact CRQ2-1 for disengaging the plunger 43 through a solenoid SOLI and a hydraulic actuator (not shown) activated by the solenoid SOLI.

Referring to the upper half of FIG. 6, a plurality of contacts T1, T2, T4, T8, T10, T20 and T40 for the command use of the tool number, which are operated to be opened or closed by the tape command signal, and relays CRT1, CRT2, CRT4, CRT8, CRT10, CRT20 and CRT40 are connected between the lines 100 and 200.

Contact TF, shown at the uppermost portion of FIG. 6, is closed with a lesser delay time than the other contacts to prevent the contacts T1 through T40 from misoperating, due to the irregularity of the opening and closing action thereof, and is opened after a short duration.

The limit switch-contacts LS1, LS2, . . . LS40 and LSP, shown in the lower half of FIG. 6, are the respective contacts of the limit switches, which are arranged in the above-mentioned reading device 55, and are connected to relays CRL1, CRL2, . . . CRL40 and CRLP, respectively, as well as to the contact CRD-1 of the relay CRD which is connected to the above-mentioned limit switch LSD. The closing of this contact CRD-1 operates so as to align the starting time of the operations of the respective relays CRL1, . . . , and CRLP so that the actual position of the magazine can be prevented from being misread.

The limit switch LSP is applied for the parity check use of the codes.

FIG. 7 shows the binary to decimal converting circuit in which the binary code is converted to the decimal code representing the tenth figure of the decimal tool number. The relays CRLOO, . . . , and CRL50 shown in the upper half of FIG. 7 are connected to the contacts of the relays CRL10, CRL20 and CRL40, shown in the lower half of FIG. 6, which operate responding to the binary codes.

For example, the closing of the limit switches LS10 and LS40, FIG. 6, corresponds to 50 of the decimal digits, and accordingly, the contacts CRL40-2 and CRL10-6, (FIG. 7) are closed to energize the relay CRL50 only. Therefore, it will be understood that the fifties' storing region including positions 50 through 59, corresponds to the tool change position TCP.

The relays CRT00 . . . , and CRT50 have almost similar circuit arrangement and are connected to the contacts of the respective relays CRL10, CRL20 and CRL40 (FIG. 6), which operate responding to the tape command signals. These relays CRL00, CRL10 . . . CRL50 and CRT00, CRL10, . . . , and CRT50, (FIG. 7), correspond to the respective storing regions 00, . . . , and 50, (FIG. 4), which are formed by grouping the sockets 22a of the magazine, (FIG. 1). Therefore, as shown in FIG. 8, the contacts CRL00-1, . . . CRL50-1, and CRT00-1, . . . CRT50-1 are arranged so as to discriminate the difference between the storing regions belonging to the tool-change position TCP and of the commanded tool. The relay CR10 is energized only when both above storing regions are identical, and is provided with the self-holding circuit derived from the

self-contact CR10-1 thereof. Accordingly, when the storing region of the commanded tool is discriminated to be identical with the storing region of the actual tool, the relay CR10 closes the contact CR10-2, (FIG. 11), and the contact CR10-3, (FIG. 12) so that the discrimination of the shorter rotating route of the magazine is performed by applying the unit figure-code.

FIG. 9 and FIG. 10 show the rotating direction-discriminating circuits in the case of different storing regions.

The relay CRCCW, (FIG. 9) directs the magazine to rotate in a counterclockwise direction.

The circuit, FIG. 9, is composed of the contacts of the above-mentioned relays CRL00, . . . , and CRL50 so that the logical conditions of Table 2 is satisfied, and is connected to the electric power supply line 100 through the contacts CR100-1 and CRTF-2. 2.

The contacts CR10-4 and CRCW-4 are inserted, in series, into the circuit for the purpose of interlocking between the forward and reverse rotating directions.

The line 110, FIG. 9, which is connected to the connecting points of the contacts CR100-1 and CRTF-2 at an end thereof, is connected to the line 110, (FIG. 10) at the other end thereof.

Also, the line 120, (FIG. 9), which is connected to the other connecting point of the contact CRTF-2 at an end thereof, is connected to the line 120, FIG. 10 at the other end thereof. The contact CR1-2, 2, (FIG. 9) is connected to the circuit in parallel with the contacts CRL00-, . . . CRL50- and CRT00-, . . . , CRT50- so that the relay CRCCW is energized also when the magazine is directed by the relay CR1, (FIG. 11), to be rotated in a counterclockwise direction as a result of the discrimination of the unit figure-code. The self-contact CRCCW-3 of this relay CRCCW is connected to the line 110 to constitute a self-holding circuit. Therefore, when the magazine is directed to be discriminated in its rotating direction, and the relay CRCCW is energized by closing the contact CRTF, the self-holding circuit is set in the self-holding situation so as to maintain the situation until the commanded tool is indexed to the tool-change position TCP. When the commanded tool is selected, the relay CR100 in the coincidental circuit of FIG. 13 is energized to assure the proper selection. When the relay CR100 is energized, the contact CR100-1, (FIG. 9), is opened to release the self-holding condition of the above-mentioned self-holding circuit and to cut the electric power source of the magazine-drive motor M1. Subsequently, the indexing of the magazine is completed.

The relay CRCW of FIG. 10 directs the magazine to rotate in a clockwise direction and the relay circuit, FIG. 10, is constituted from the contacts CRLOO-, . . . , CRL50- and CRT00-, . . . , CRT50- which are connected between the lines 110 and 120 so that the logical condition of Table 1 is satisfied. Also, to this relay CRCW, there is connected the contact CRCCW-4 in series for the purpose of interlocking between the forward and reverse direction. Further, the contact CR2-2 is connected between the lines 110 and 120 in parallel with the above-mentioned contacts, so that the magazine is also directed to rotate in a clockwise direction by energizing the relay CR2, FIG. 12 as a result of the discrimination of the unit figure-codes.

Also, in the case of relay CRCW, the self-contact CRCW-3 is inserted into the relay circuit in series with the line 110, and the self-holding circuit is constituted so that the magazine is maintained to rotate in a clockwise direction until the contact CR100-1, (FIG. 9) is opened by energizing the relay CR100, (FIG. 13).

FIG. 11 and FIG. 12, as explained before, show the direction-discriminating circuit whereby the rotating direction of the magazine in a clockwise or counter-clockwise direction is discriminated responding to the code of the unit figure in the case when the tool-storage region corresponding to the tool-change position TCP and the tool-storage region of the subsequent commanded tool are identical. These circuits operate in response to the opening of the contacts CR10-2 and CR10-3 of the relay CR10, FIG. 8.

The relay CR1, (FIG. 11) directs the magazine to rotate in a counterclockwise direction.

This circuit is connected between the lines 110 and 200 while being so arranged by the contacts CRL1-1, . . . CRL8-1, and CRT2-1, . . . CRT8-1, that the logical condition for the counterclockwise direction of Table 3 is satisfied, and contains the self-holding circuit provided by the self-contact CR1-1.

The relay CR2, FIG. 12, directs the magazine to rotate in a clockwise direction. This circuit is also connected between lines 110 and 200 while being so arranged by the contacts CRL1-1, . . . CRL8-1, and CRT2-1, . . . CRT8-1, that the logical condition for the clockwise direction of Table 3 is satisfied, and contains the self-holding circuit provided by the self-contact CR2-2. Consequently, when both tool-storage regions are discriminated to be identical, the contacts CR10-2, (FIG. 11) and CR10-3, (FIG. 12) are closed and subsequently, the relay CR1 or CR2 is energized to indicate the rotating direction of the magazine with closing of the above-mentioned contact CR1-2, (FIG. 9) or CR2-2, (FIG. 10), respectively. As a result of this, the magazine is discriminated in its shorter rotating route while responding to the unit figure-code so as to effect the shortening of the large amount of tool-selection time.

Especially, in this case of the identical region, since the commanded tool is necessarily near the tool change position, the tool-selection time may become remarkably short according to the above-mentioned discrimination of the shorter rotating route of the magazine.

The operation of the direction-discriminating circuit is described hereunder according to Tables 1, 2 and 3.

Provided that the tool No. 17 is commanded subsequent to the tool of No. 53, limit switches LS1, LS2, LS10 and LS40 have already closed to energize relays CRL1, CRL2, CRL10 and CRL40, contacts T1, T2, T4 and T10 are closed in accordance with an index position-selecting information stored in a permanent record, such as a punched tape, thereby energizing relays CRT1, CRT2, CRT4 and CRT10 in FIG. 6.

In FIGS. 7 and 8, relay CRT50, is energized and relay CRL10, has already been energized. In the direction-discriminating circuit (FIG. 9) formed in accordance with Table 2, relay CRCCW is energized by closing of contacts CR100-1, CRTF-2, CRL50-2, CRT10-4, CR10-4, and CRCW-4. The magazine 22 is rotated in the CCW direction by the energization of relay

CMCCW, as aforementioned with respect to FIG. 5, till the relay CR10 of the detecting circuit of FIG. 8 is energized by closing contacts CRL10-1 and CRT10-1.

The energization of relay CR10 de-energizes the relay CRCCW by opening of normally closed contact CR10-4, and close the normally open contacts CR10-2 and CR10-3 of FIGS. 11 and 12, wherein the rotating directions of magazine 22 is discriminated by relays CRL1, CRL2, CRT1, CRT2 and CRT4 corresponding to the unit figures 3 and 7 of index position numbers. The relay CR1 of direction-discriminating logical relay circuit (FIG. 11), which is formed by the logical condition of Table 3, is energized through the closing of contacts CR10-2, CRL8-1, CRL4-1, CRL2-2, CRL1-4, CRT4-2 and interlocking relay CR2-2. Furthermore, the magazine 22 is rotated in the CCW direction by the energization of relay CR1 till the relay CR100 of the coincident circuit (FIG. 13), which is described below, is energized.

FIG. 13 shows the coincidental circuit wherein the relay CR100 is energized when the commanded tool is indexed to the tool-change position. Accordingly, the contacts CR100-1, (FIG. 9) and CR100-2 (FIG. 8), are opened to deenergize each relay with cutting of the electric power source of the motor M1 so as to stop the rotation of the magazine. This relay CR100 is connected to each contact of the relays CRT1, . . . , CRT40 and CRL1, . . . , and CRL40 of FIG. 6, and CRT10, . . . , CRT50, and CRL10, . . . , CRL50, of FIG. 7, between the electric power supply lines 100 and 200.

Hereinafter, the symbols l_1 through l_{16} , shown in FIG. 13, will be given to each row of these contact-groups of the circuit for the purpose of clarification.

The symbols l_1 through l_6 are applied for comparison of the tenth figure-codes.

Both contacts CRL for reading the instant position of the magazine and CRT for representing the commanded tool, which have coincidental numbers, respectively, are connected in a series to make a pair thereof and the combination of the pairs arranges the circuit. For example, the row l_1 is composed of series circuits of the normally closed contacts given the code numbers 40, 20 and 10, and consequently, when the tenth figure is 0, that is, the tool-storage region 00, (FIG. 4), of the magazine is indexed to the tool change position TCP, the line 130 is interconnected electrically to line 100. In the case of row l_2 , a pair of normally opened and series-connected contacts CRL10-8 and CRT10-8 is connected in parallel with a pair of normally closed and series-connected contacts CRL10-7 and CRT10-7, and when the contacts CRL10-8 and CRT10-8 are closed, that is, the tool-storage region 10 is indexed to the tool-change position TCP, the line 130 is interconnected electrically to the line 100.

The rows l_7 through l_{16} are applied for comparison of the unit figure-codes.

The whole circuit is constituted from the combination of pairs of the series-connected contacts CRL and CRT for reading the actual position of the magazine and for representing the commanded tool, respectively, both of which have coincidental numbers. Accordingly, the contact-groups of the whole circuit are connected between the line 130 and the relay CR100. The row l_7 is composed of the series circuits of the normally closed contacts given the code-numbers 8, 4, 2 and 1, and

when the unit figure-code is 0, the line 130 is interconnected electrically to the line 200.

Therefore, if the tool of the code-number 0 is commanded, the relay CR100 is energized only when this tool is indexed to the tool-change position. Similarly, for example, if the tool of the code-number 13 is commanded, the relay CR100 is energized by the closing of the contacts of the row l_2 and the contacts of the row l_{10} , that is, the tool of the code-number 13 is indexed to the tool-change position.

Thus, the magazine is controlled to rotate in the shorter route after the rotating direction thereof is determined by each direction discriminating circuit previously described, and thereafter, when the commanded tool is indexed to the tool-change position by the coincidental circuit of FIG. 13, the rotating motion of the magazine is stopped. The direction-discriminating device, previously described, is provided with the first direction-discriminating means to determine the rotating direction of the magazine, which makes the tool-receiving portion-identifying code of the magazine capable of discriminating the tool-storage regions from each region, as well as the second direction-discriminating means which makes the above-mentioned identifying code determine the rotating direction of the magazine in the identical region, in the case of the identical storage region.

Consequently, if the number of tools increases or decreases, it is possible to deal with this. Next, referring to FIG. 14 through FIG. 16, another embodiment of the direction-discriminating circuit for the magazine wherein the number of tools is 40, will be explained.

The magazine is divided into four storage regions by adopting the binary-coded decimal code similar to the aforescribed embodiment, and the logic for discrimination of the rotating direction can be set almost similarly to the aforescribed embodiment.

FIG. 15 shows a circuit arrangement only for detecting whether the tool storing regions of the instant and subsequent commanded tools are identical.

In FIG. 16, a circuit arrangement is shown for discriminating the rotating direction of the magazine when the tool storing regions of the instant and subsequent commanded tools are different. It is a completely different point of this embodiment from the previous embodiment that the above-mentioned discrimination of the rotating direction of the magazine is carried out by the binary code not being converted to decimal code. Thus, when the number of tools is reduced, the logical circuits for discriminating the difference of the storing regions and the rotating direction of the magazine can be constituted effectively without becoming complicated, even if the binary to decimal converting circuits are omitted.

In FIG. 17, there is shown only a coincidental circuit to compare the tenth figure-codes, but does not show a comparing circuit for the unit figure codes.

This is because the circuit shown in FIG. 13 of the previous embodiment can be converted to this embodiment by replacing the group of contacts l_1 to l_6 with the group of contacts shown in FIG. 17. This replacement can be accomplished by connecting the line 130 of FIG. 17 to the line 130 of FIG. 13.

According to the use of these replaced circuits, the rotating direction discriminating circuit of the previous

embodiment shown in FIG. 11 and FIG. 12 is capable of being converted to this embodiment.

In the above explanation of both embodiments of the invention, the most typical binary-coded decimal system is adopted for the identifying code, but, of course, other coding systems are applicable. Also, the construction of the magazine is never limited to the above-mentioned chain type, but another type, for example, a drum type, a ring type and a plate type may be adopted.

Therefore, it will be understood that variations and modifications of the above embodiments can be effected within the spirit and scope of the present invention as described above.

What is claimed is:

1. In an indexing control device for controlling the rotation of a rotating body having at least ten spaced index positions by a motor so as to place a desired index position of said spaced index positions at a predetermined station, an improvement comprising: means identifying said index positions by applying specific identifying decimal numbers provided to each one of said index positions and coded by binary coded decimal elements, each of said numbers comprising a higher figure and a lower figure, said index positions of said rotating body being divided into a plurality of regions identified by the higher figures of said specific identifying decimal numbers; reading means operated by said binary coded decimal elements so as to produce an identifying signal in accordance with one of said index positions which is actually placed at said predetermined station; command circuit means capable of commanding a desired index position to be placed at said predetermined station; first discriminating circuit means including relays corresponding to the higher figures of said specific identifying decimal numbers which are present in accordance with said desired index position so as to discriminate the rotating direction of said rotating body in response to said identifying signal of the higher figure when the region containing said desired index position is different from the region containing an actual index position placed at said predetermined station; detecting circuit means connected to said command circuit means and said reading means for producing a detecting signal when the region containing said desired index position is identical with the region containing said actual index position; second discriminating circuit means which are preset in accordance with said desired index position for discriminating the rotating direction of said rotating body in response to said identifying signal of the lower figure of said specific identifying decimal numbers, said second discriminating circuit means starting the operation thereof according to said detecting signal; coincidence circuit means preset in accordance with said desired index position and operated in response to said identifying signal which produces a coincidence signal when said desired index position is placed at said predetermined station; and motor controlling means which is activated by said first and second discriminating circuit means for rotating said rotating body in the discriminated direction to index said desired index position into said predetermined station by the shorter rotating route and for stopping the rotation of said rotating body in response to said coincidence signal.

2. An indexing control device according to claim 1, wherein said identifying means comprises a coding drum having a plurality of divided columns thereon corresponding to said index positions, respectively, and rotating synchronously with said rotating body, said binary elements selectively arranged on said column to represent said identifying decimal number while being coded in a binary code.

3. An indexing control device according to claim 2, wherein said decimal number is changed by the arrangement of said binary elements to binary coded decimal code.

4. An indexing control device according to claim 3, wherein said reading device comprises a plurality of switches arranged in face of rows of said column, respectively, to be operated by said binary elements, a plurality of relays connected to said switches, respectively, for providing said binary coded decimal code of said index position indexed at said predetermined position to said detecting circuit means, said first and 20

second discriminating means and said coincidence circuit and an alignment contact connected to said switches to align a starting time of operations of said individual relays.

5. An indexing control device according to claim 1, wherein said first and second discriminating circuit means comprise a logical relay circuit for discriminating a clockwise rotation of said rotating body in accordance with a logical condition preset by said commanding circuit and another logical relay circuit for discriminating a counterclockwise rotation of said rotating body in accordance with a logical condition preset by said commanding circuit, respectively.

6. An indexing control device according to claim 5, wherein said first and second discriminating circuits further comprise a circuit for inter-locking between said clockwise and counterclockwise rotations, respectively.
